UNITED STATES PATENT OFFICE

113,353

DESIGN FOR A SHOE

Isadore Sabel, West Philadelphia, Pa., and Laurie S. Macdonald, Brockton, Mass.

Application December 23, 1937, Serial No. 73,834

Term of patent 3½ years

To all whom it may concern:

Be it known that we, Isadore Sabel and Laurie S. Macdonald, citizens of the United States and residing, respectively, in West Philadelphia, in the county of Philadelphia and State of Pennsylvania, and in Brockton, in the county of Plymouth and Commonwealth of Massachusetts, have invented a new, original, and ornamental Design for Shoes, of which the following is a specification, reference being had to the accompanying drawing forming part thereof, in which the figure is a perspective view of a shoe showing our new design, the opposite side of the same presenting substantially the same appearance as the side shown.

We claim:

The ornamental design for a shoe, substantially as shown and described.

LAURIE S. MACDONALD.

ISADORE SABEL.
